UNITED STATES PATENT OFFICE.

MORTON H. DAGUE, OF NEWPORT, ARKANSAS.

PAPER BOX.

1,157,298.

Specification of Letters Patent. Patented Oct. 19, 1915.

Application filed December 19, 1914. Serial No. 878,167.

To all whom it may concern:

Be it known that I, MORTON H. DAGUE, a citizen of the United States, residing at Newport, in the county of Jackson and State of Arkansas, have invented certain new and useful Improvements in Paper Boxes, of which the following is a specification, reference being had to the accompanying drawings.

This invention relates to certain improvements in paper boxes and has relation more particularly to a device of this general character adapted to be produced from a single blank; and an object of the invention is to provide a box having novel and improved means whereby the same may be readily and effectively maintained in operative assemblage.

Furthermore, it is an object of the invention to provide a novel and improved box of this general character including a supplemental closure medium and wherein such supplemental closure medium comprises relatively movable sections provided with coacting means whereby said sections may be interlocked in applied adjustment.

The invention consists in the details of construction and in the combination and arrangement of the several parts of my improved paper box whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is a plan view of a blank from which a box constructed in accordance with an embodiment of my invention is adapted to be produced; Fig. 2 is a view in perspective of an assembled box with the top section in open position; Fig. 3 is a fragmentary sectional view taken substantially on the line 3—3 of Fig. 2; and Fig. 4 is a fragmentary sectional view taken substantially on the line 4—4 of Fig. 2, with the top section shown in closed position.

As disclosed in the accompanying drawings, B denotes a blank from which a box constructed in accordance with an embodiment of my invention is adapted to be pro-

duced and of which 1 is a front section, 2 a bottom section, 3 a back section, 4 a top section, and 5 a tuck flap. The front section 1 is provided with the longitudinally disposed slits 6 and is also provided with the end flaps 7, said end flaps 7 being provided with the slits 8 adapted to have inserted therethrough the tongues 9 carried by the end flaps 10 of the back section. The end flaps 10 are provided with the top flaps 11, one of such flaps 11 having produced transversely in its outer extremity a slit 12 through which is adapted to be inserted the locking tongue 14 projecting forwardly from the outer end of the opposite top flap 11 at substantially the transverse center thereof. The bottom section 2 is also provided with end flaps 15, said flaps, as herein disclosed, being of a length less than the length of the end flaps 7 and 10, as is believed to be clearly shown in Fig. 1 of the accompanying drawings. The tuck flap 5 is provided with the hook tongue 16 adapted to be inserted through the slit 6 of the front section 1 in a manner and for a purpose which is believed to be self-evident. It may also be well to state at this time that the tongue 14 is also of hook formation.

In assembling the device, as herein set forth, the end flaps 7 are adapted to overlie the end flaps 15 and the flaps 10 are adapted to overlie the flaps 17 so that the tongues 9 may be readily inserted through the slits 8. By this arrangement, the box is effectively maintained in operative assemblage, and in practice has been found to possess a maximum of strength and especially at the ends thereof which in the completed box, and as particularly illustrated in detail Fig. 3, are composed of three plies or laminations. The top flaps 11 are then in position to be folded over the open face of the box, as particularly shown in Fig. 2, and with the tongue 14 disposed through the slit 12, such top flaps are effectively maintained in closed adjustment and serve with advantage as a supplemental closure member. The tuck flap 5 is adapted to overlie the front section 1 with the hook 16 thereof disposed through the slit 6 whereby it will be readily perceived that the top section 4 will be effectively locked in closed position. It might be well to state at this time that under certain conditions it may be advisable to omit the interlocking coaction between the top flaps 11.

It is thought to be self-evident that the hooks 14 and 16 may be readily and conveniently interlocked with their respective slits 12 and 6 by relative lateral movement between the top flaps 11 and the front section 1 and the tuck flap 5.

From the foregoing description, it is thought to be obvious that a paper box constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A box of the character described comprising a front section provided with end flaps having slots produced therein longitudinally thereof and at their inner extremities, said

front section intermediate its length being provided with a longitudinally disposed slot, a bottom section provided with end flaps, a back section provided with end flaps, said end flaps of the back section being provided with top flaps and with depending tongues insertible through the slots of the end flaps of the front section, a top section, 35 a tuck flap carried by the top section, said tuck flap being provided with a hook tongue insertible through the slot of the front section, the outer end portion of one of the top flaps being provided adjacent its outer extremity with a transversely disposed slit, and the outer portion of the second top flap being provided with a hook tongue adapted to be inserted through the slit of the first mentioned top flap, the end flaps of the bottom section being of a length less than the end flaps of the front and back sections.

In testimony whereof I hereunto affix my signature in the presence of two witnesses.

MORTON H. DAGUE.
